SLAB FLOORING

Theodore Barbato, White Plains, N. Y.

Application August 10, 1939, Serial No. 289,351

5 Claims. (Cl. 72—66)

The present invention relates to slab floorings in which bays between girders are spanned by a system of ribs of reinforced concrete which serve as end supports for a system of hollow tile arches, each such arch consisting of a plurality of tiles bonded one to another by concrete fills, and the several arches being laterally juxtaposed to form a tile flooring which may be continuous except as interrupted by the girders, ribs and fills.

In the type of flooring with which the invention is particularly concerned, the tiles are preferably set together in situ to form the arches; being supported by scaffolding at opposed edges of the tiles intermediate the concrete ribs, and being end-positioned on the reinforcing metal of the ribs before concrete is poured around such reinforcements; thus to provide a temporary support for the arches which will suffice to bear the load of all construction work thereafter to be performed thereon, including the load of any and all unset concrete which may be applied to the flooring.

In a flooring of this general character, an object of the invention is a reinforced concrete rib, for the purposes aforesaid, having as the reinforcement thereof a metal truss of such nature and so combined with the concrete as to result in a beam or rib having structural and economical advantages now to be set forth, and which have heretofore been unattainable.

A rib heretofore devised for use in a system such as mentioned consists of an I beam embedded in concrete. The lower flanges of such I beam afford excellent supports for tiles, and permit of some adjustability of the tiles with respect thereto, to allow for irregularities in construction work. Also, when the concrete is poured around the I beam between the same and the ends of the tiles, the tiles are bonded to the I beam right and left thereof. Such a rib is not, however, a reinforced concrete rib in the true sense of the term: and, because of existing standardizations of I beams, lacks some of the flexibility desired in meeting specifications which vary widely as to floor thickness and load capacity.

For such an I beam, I have substituted a truss of somewhat similar cross section, but which consists of an openwork web made up of struts to which angle irons are welded at top and bottom: and in such substitution the objections just noted in the use of I beams disappear, and a number of advantages are had which are not to be had in the use of I beams.

Firstly: The concrete when poured or tamped around the truss will pass through the web between the struts thereof, and between the angle irons along those reaches thereof where no strut is present, and down around and under the angle irons: the struts serving to space laterally apart opposed angle irons for such flow of concrete therebetween. Instead, therefore, of the concrete being formed in weakly connected masses 10 right and left of the web, as in the case of an I beam, it here takes the form of a true monolith, reinforced at the bottom of the truss by angle irons which act as rods to take tensional strains, and from top to bottom by web struts 15 which take shearing stresses. The top angle bars act as compression members in the carrying of construction loads prior to setting of the concrete: and in the completed floor add their compression strength to that of the concrete. The struts at their points of connection to the bars 20 act as blocks, dogs, or lugs on the bars, holding the latter against longitudinal slip or shift in the concrete.

Secondly: In the use, aforesaid, of angle irons, 25 a reinforcing bar is had which, for a given selected cross section, or strength, presents a more extended and effective surface area for bonding thereof to the concrete than is presented by bars of round or other cross section, adaptable for the support of tiles thereon. As will hereinafter 30 be noted, each angle iron bonds with the concrete at both the front and back faces of its vertical member, and at the under face of its horizontal member: so that the upper face of 35 the horizontal member is not required for bonding with the concrete, and may be occupied by the ends of the tiles to any extent conformable to the adjustment of the latter with respect to the truss in the laying of the arches.

Thirdly: Angle irons, (as distinguished from I beams), may be had of almost any desired size, and may be as thick or thin as may be required for any given strength, rigidity, or depth of flooring,—and the same applies to the 45 truss webs. The truss structure, therefore, is of great flexibility as to design. This flexibility is such, for instance, as to open the way for the use in the present invention of reinforcing bars of alloys having vastly greater tensile strength than ordinary steel,—bars which as to weight and cross section for a given tensile strength may be less than 60% of that of steel, but which nevertheless will require surface area, for bonding with the concrete, no less extensive than 55 other bars. In the truss and the use thereof

in the present invention full advantage may be taken of the great strength of such alloys as a means for reducing floor weight, because no matter how small the weight or total cross sectional area of an alloy reinforcement, it will, when properly designed as an angle iron, present all necessary surface area for bonding with the concrete.

It is obvious that since the truss is an assembly of parts welded or otherwise put together, the size, and relative size, and dimensions of top and bottom bars, and of the web, and the number and positioning of struts in the web, are freely variable, and any combination of truss elements may be selected to meet design requirements and to obtain economically a ribbed floor construction of maximum strength.

As hereinafter shown, the faces of the tiles, opposed to the trusses, are shaped to diverge or slant broadly away from the base of the truss to the floor surface, so as to permit of a concrete fill which when set will be a real concrete beam of substantial structural strength; and to the strength and rigidity of which is added that of the tiles themselves, by reason of the firm bonding and adhesion of the tiles to the concrete.

A feature of the invention is that the open construction of the trussed reinforcing member will permit conduits, pipes, etc., to pass therethrough, enabling such installations to be embedded in the slab, instead of being carried on the top of the truss. This feature enables the slab to be finished monolithically without addition of excessive and costly fills to cover these conduits, pipes, etc. This feature also tends to eliminate cracks in the finished floor construction, which might otherwise be caused by expansion and contraction of conduits and pipes installed too near the finished surface.

It will be understood that for floors of greater strength, and where space permits, a fill of concrete may be laid in a sheet over the trusses and tiles so as to monolithic with the fills around the trusses and therewith to form a T-beam concrete structure. It has also hereinbefore been mentioned that where tile is juxtaposed to tile in any arch, the opposed tile faces are bonded by concrete fills which constitute concrete blocks or beams running parallel to the trusses. These fills are made concurrently with the fills at the trusses and with any surfacing fill, so that where the latter is present it will form monolithic T-beam structures with the fills between tiles.

The tiles where they oppose one another in an arch preferably have their faces so inclined upwardly and outwardly with respect to each other as not only to form a trough or mold of size sufficient for the formation therein of a bonding block or beam of substantial structural strength, but so as to permit their lower opposed edges to be juxtaposed to close such trough or mold at the bottom thereof and to present an all-tile, continuous under surface or ceiling, to which plaster may be applied without chance of ultimate discoloration thereof such as commonly occurs where plaster is applied to ceiling surfaces of two or more different materials.

I am, of course, aware that trusses, more or less resembling the truss of the present invention, have been used in connection with floorings. In such prior use of trusses, however, the truss has not been in the plane of the floor slab and has not been a metal reinforcement for any concrete rib of such slab. It has been a truss on the top of which the slab as a whole was set.

The above and other objects and features of the invention will more fully appear in connection with the accompanying drawings, in which:

Fig. 1 is a top plan view of a section of flooring embodying the present invention: the concrete fills being incompletely applied thereto.

Fig. 2 is an enlarged cross sectional view taken on the line 2—2 of Fig. 1.

Fig. 3 is an enlarged cross sectional view taken on the line 3—3 of Fig. 1.

Fig. 4 is a full-size view, taken in cross section through the lower portion of one on the reinforced concrete beams and through the ends of two tiles supported thereon at opposite sides thereof.

Fig. 5 is a view in side elevation of one of the reinforcing trusses, showing a wall support for one end thereof and a girder support for the other end thereof, and showing also the manner in which trusses in different and successive bays may be united and made integral in effect by plates connecting the same over the girders.

Fig. 6 is a view in cross section on the line 6—6 of Fig. 5.

Fig. 7 is a view in cross section on the line 7—7 of Fig. 1, showing tiles which have their upper parts cut away to permit conduits to be laid thereon in the plane of the floor slab, and in such plane to be passed through the open-work of the trusses.

Referring to the drawings, there is shown in Fig. 5 one of the building walls 10, and one of the girders 11 which define the bays of the building structure. Spanning the bays and having end supports on the girders 11, or, as in Fig. 5, on a girder 11 and wall 10, are trusses 12, spaced apart a distance determined by the selected length of tile arch, see Fig. 2.

In Fig. 5 each truss 12 is shown as comprising a system or succession of struts 13. To the right and left faces of the struts, at the upper ends thereof, are welded or otherwise secured two angle irons 14 and 15, respectively. The horizontal flanges of these irons are shown as in the same plane, and as flush with or slightly above the ends of the struts. To the right and left faces of the struts, at the lower ends thereof, are welded or otherwise secured two other angle irons 16 and 17, respectively. The horizontal flanges of angle irons 16 and 17 lie in the same plane, flush with or slightly below the lower ends of the struts 13.

The particular number and disposition of the struts 13 need not be that shown in Fig. 5, but may be varied according to circumstances. It has hereinbefore been stated that these struts have, among other functions, the function of resisting shearing stresses. For this purpose they may be heavier or more numerous near the ends of the trusses than towards the center. Together, the struts form an open-work web connecting the angle irons, the truss as a whole having somewhat the cross section of an I-beam. As hereinbefore explained, the size and weight of the angle irons, and the length and thickness of the arms thereof, and the height and thickness of the web, are all subject to variation at will to meet in the most economical manner the specifications or requirements as to strength, rigidity, weight, and depth of any flooring.

The shaded part of Fig. 1 defines one of the tile arches spanning the space between two of the trusses 12. This arch is shown in cross section in Figs. 2 and 3. It is shown as composed of two blocks or tile units 18 and 19, but if de-

sired, the arches may be composed of more than two tile units. As shown in Fig. 1, there is, between any two trusses 12 a succession of such arches, laterally juxtaposed, one to the other, to form a continuous flooring.

Before the arches are laid, there is erected a scaffolding comprising a board 20, see Fig. 2, positioned temporarily to support the tiles at the sides thereof opposed to one another in the successive arches. Each of the tile units 18 and 19 abuts one of the trusses 12: and in that face of the tile which abuts a truss is a slot 21. Into the slot 21 in the tile unit 18 protrudes the horizontal wing 22 of the angle iron 17 at the left of a truss 12; and into the slot 21 in the tile unit 19 protrudes the horizontal wing 23 of the angle iron 16 at the right of a truss 12. The arches are thus temporarily supported, centrally by the board 20, and at their ends by the angle irons at the feet of the trusses 12: and as so supported, have their under surfaces 24 in horizontal alignment.

The opposed faces 25 and 26 of the tiles 18 and 19 in any arch are shown as inclined upwardly and outwardly with respect to each other from the bases to the tops of the tiles, to form molds or troughs 27 into which concrete may be poured or tamped which, when set, will form blocks 28, see Fig. 3, of concrete permanently bonding together the several units of the arch, and giving to the arch the great compressive strength of such concrete block. When the troughs 27 in successive arches are in alignment, the blocks 28 will assume the form of concrete beams or ribs extending crosswise of the arches intermediate and parallel to the trusses 12, thus further increasing the compressive strength of the floor. To assure the creation of blocks or ribs of true concrete, the troughs 27 should be of width and depth sufficient to allow for absorption of water from the mix by the tiles.

The shape and setting of the opposed faces 25 and 26 of the tiles 18 and 19 is such as to close the troughs 27 at the bottom, except for a clearance 29 at the base of the tiles. Similar clearances 30 are shown between the ends of the tiles below the trusses 12. These clearances are too small to allow leakage of concrete therethrough. They are so small that the under surfaces 24 of the tiles form an all-tile, or one material, continuous ceiling surface: thus precluding the discoloration of plaster thereon, arising from variations in the effects of light passing through plaster laid over materials of different densities and nature.

The clearances 29 and 30 have several important purposes. Firstly, they allow for any slight irregularities in the placement of the trusses 12. Secondly, they permit the tile units, by reason of the slots 21 therein, to be hooked onto the wings 22 and 23 of the angle irons 16 and 17 at the feet of the trusses, and thereafter to be swung down upon the boards 20. Thirdly, they serve as means whereby to key plaster or other ceiling to the under face of the flooring.

For economy in construction, it is desirable that a minimum of scaffolding be required, and that the same be removable with as little delay as possible. Due, however, to the fact that concrete may be laid much faster than it will set, the maintenance of an extensive scaffolding for construction loads has ordinarily been necessary. The situation is otherwise with the present invention. Here the boards of the scaffolding are no part of any forms within which to cast the

concrete: the tiles of themselves are the complete forms: and, as above pointed out, together present an all-tile bottom surface, continuous except for joints 29 and 30 which are substantially concrete tight. The trusses support the tiles at the ends of the arches: and the only scaffolding required is one to support the tiles along the lines of the boards 20.

This scaffolding may, of course be left in place 10 until the concrete has set, in which event it would have to be a more or less extensive scaffolding. Having served its initial purpose as a platform on which to lay the tiles, it may, however, be replaced, so far as the carrying of construction 15 loads is concerned, by wedges 31, see Figs. 1 and 2, driven into the troughs 27, to lock the tiles one to another, and to make the arches self-sustaining. A small scaffolding, progressively movable with the driving of the wedges, will therefore here suffice for the laying of an entire floor.

In connection with the use, aforesaid, of wedges 31, the clearances 29 and 30 are seen to have a further useful purpose. They allow for a spreading apart of the tiles 18 and 19 by the 20 wedges, so that the tiles, at the inner ends of 25 their slots 21, may be jammed tightly against the ends of those wings of the angle irons 16 and 17 on which the ends of the arches are supported. These slots 21 are shown as having their 30 lower walls inclined downwardly as at 32, not only to allow for the swing, aforesaid, of the 35 tiles, in hooking them to the trusses and positioning them upon the boards 20, but to provide for a concrete fill, hereinafter mentioned, below the bars 16 and 17.

Upon reference to Figs. 2 and 3, it will be noted 40 that the tiles are so shaped that their opposed faces 33 and 34 at the trusses 12 diverge broadly upward from the angle irons at the feet of the 45 trusses to the tops of the tiles. This provides for a fill of concrete between the tiles, sufficient, with the trusses 12, to form a true reinforced concrete beam or rib for the flooring, bonding together the arches on opposite sides of the trusses. 50 This shaping of the tiles also assures clear 55 passage for the concrete to the truss and tile surfaces to be bonded thereby.

Referring to Fig. 5, it will be noted that the 55 end struts 35, by which the trusses are supported 60 on the lower flanges 36 of the girders 11, are extended below the bars 16 and 17. Where trusses of an end bay are to rest upon a wall 10, they 65 may be provided with vertical strut members 37 having foot plates 38. The members 37, like the 70 end struts 35, will ordinarily be heavier, that is to say, broader (see Fig. 5), than the other struts 13, but of the same thickness: so that all truss struts may lie in a common plane between, and welded or otherwise secured to, opposed angle irons, 14 and 15 at the top of the truss, and 16 and 17 at the bottom thereof.

The trusses in one bay may be made continuous 75 with those in a next succeeding bay by means of plates 39, see Fig. 5. These plates extend 80 from one truss to another across the top flanges 85 of the intermediate girder 11. Opposite ends of the plates are welded or otherwise secured to the trusses: and, for greater rigidity, the plates 90 may also be welded to the top faces of the girders, intermediate the trusses which they connect.

It has been stated that the open-work of the 95 truss webs 13 permits conduits, pipes, etc. to pass therethrough, so that the latter need not be laid at the top of the flooring. For this purpose, see Figs. 1 and 7, those tiles 18 and 19 which are to

be crossed by the conduits may be cut down to the plane of the top of the webs 18' and 19' of the tiles, and the conduits laid on such webs 18' and 19'. In Fig. 7 such a conduit 60 is shown extending through the open-work of the truss webs 13 and over the tile webs 18' and 19'.
5

The flooring elements having been set together as above described, and as shown in Figs. 1 and 2, the structure is ready for the concrete fills. The fill at the trusses 12 will pass down around the trusses, through the open-work thereof, and into contact with all surfaces of the struts 13, 35 and 37 not covered by the angle irons 14, 15, 16 and 17. Along those reaches of the lower angle irons 16 and 17 between such points 41 thereof, where the struts are welded to the bars, the concrete will flow between the opposed and spaced vertical faces, 42 and 43 respectively, of the upright wings 44 and 45 of angle irons 16 and 17, and into the space formed by the notches 21 in the tiles, below the bars 16 and 17. In so doing, it will contact the inclined tile surfaces 32 of the notches or slots 21, and the entire under surfaces of the horizontal wings 22 and 23 of bars 16 and 17; thus bonding tiles and bars firmly together over these surfaces, and over the entire opposed faces 42 and 43 of the lower bars.
10

To right and left of the truss, the fill will contact the entire faces 33 and 34 of the tiles, and the outside faces 46 and 47 of the vertical wings 44 and 45 of the lower angle bars. It will also contact whatever of the upper surfaces of the horizontal wings 22 and 23 of the bars is not occupied by the tiles 18 and 19. At the top of the truss, the concrete will flow between the angle bars 14 and 15 along such reaches thereof as lie between points 48 where the bars are welded to the struts 13, 35 and 37, and will bond to the opposed vertical faces 49 and 50 of the upright wings of these bars 14 and 15. It will also bond with the upper bars over the outer vertical surfaces of the upright wings of the bars 14 and 15: and over the entire upper and lower surfaces of the horizontal wings of the bars 14 and 15.
15

Due to the passage of the concrete through the open-work of the truss web, the concrete right and left of the truss will form a monolithic mass which, with the truss, will comprise a reinforced concrete beam securely bonded to the tiles in all possible planes of stress by reason of the concrete-contacting surfaces just mentioned.
20

At the ends of the trusses, the concrete will contact all surfaces of the struts 35 and 37, not crossed by the angle irons, and will contact all surfaces of the web and flanges of the girders 11, except such surfaces thereof as are covered by the truss-uniting plates 39 or foot plates 51 for struts 35, and it will cover the tops of any such plates 39 and 51, and will bond with the under surfaces of plates 39 where they are not crossed by the top faces of the girders.
25

The troughs 27 between the opposed tiles in the arches are filled progressively with the fillings around the trusses, thus bonding such tiles firmly together to make rigid unitary structures of the arches. If wedges 31 have been substituted for the boards 29 to carry the construction loads, they are left in place, and the fill poured or tamped over, around and under the same.
30

As hereinbefore stated, the fills at the trusses 12 and in the troughs 27 may be brought flush with the tops of the tiles, and the flooring finished in that condition, in which event the flooring will be a tile flooring having ribbings or
35

beams of concrete extending therealong at the trusses 12 and troughs 27. On the other hand, as shown at 52 in Figs. 1 and 3, the filling may be continued as a substantial layer of concrete over the tops of tiles and trusses: and such layer 52 may be laid simultaneously with the fills at trusses 12 and troughs 27, to be monolithic therewith, in which event there will be a system of integrally and monolithically connected concrete beams, of T beam cross-section, interwoven with the tile arches to form a flooring of extraordinary strength for any given weight and thickness. Where any tiles are cut down to their horizontal webs 18' and 19' for positioning of conduits thereon, the conduits are laid before the fills are made, and concrete is filled in around the same to the level of the top of the rest of the floor, as shown at 61 in Fig. 7.
40

As heretofore stated, in the reinforced beam of the present invention, the angle irons 16 and 17 are bars properly positioned to take the tensional strains. As shown in Fig. 6, the struts 13, to which bars 16 and 17 are welded, are laterally offset from the bars in such a manner as to act as blocks, lugs or dogs resisting any pull on the bars which might tend to displace the same longitudinally in the concrete. The struts 13 resist shearing stresses. The upper angle irons 14 and 15 act as compression members for construction loads, and after the concrete fills have set, continue to act as compression members in reinforcement of the concrete.
45

I claim:

1. A composite concrete and tile floor slab, comprising a system of multiple-tile, permanent-load sustaining arches, and a system of reinforced concrete ribs; the arches being spaced apart, end from end, in rows, each row constituting a succession of spans, and the concrete ribs being fills which lie between and which bond one to another the opposed ends of the arches in the several rows; the reinforcements for the concrete ribs comprising open-work webs set upright in the plane of the slab, and bars secured to and projecting laterally from the webs serving as seats for the ends of the arches, said bars being imbedded in the concrete above the base of the fills for service as true tension members therein.
50

2. A composite concrete and tile floor slab, comprising a system of multiple-tile, permanent-load sustaining arches, and a system of reinforced concrete ribs; the arches being spaced apart, end from end, in rows, each row constituting a succession of spans, and the concrete ribs being fills which lie between and which bond one to another the opposed ends of the arches in the several rows; the reinforcements for the concrete ribs comprising open-work webs set upright in the plane of the slab, and angle-irons secured to and projecting laterally from the webs serving as seats for the ends of the arches, said angle-irons being imbedded in the concrete above the base of the fills for service as true tension members therein.
55

3. A composite concrete and tile floor slab, comprising a system of multiple-tile, permanent-load sustaining arches, and a system of reinforced concrete ribs; the arches being spaced apart, end from end, in rows, each row constituting a succession of spans, and the concrete ribs being fills which lie between and which bond one to another the opposed ends of the arches in the several rows; the reinforcements for the concrete ribs comprising open-work webs set up-
70

right in the plane of the slab, and bars secured to and projecting laterally from the webs serving as seats for the ends of the arches, said bars being imbedded in the concrete above the base of the fills for service as true tension members therein; the several tiles which make up each multiple-tile arch being of shape and size to permit of independent manipulation thereof for seating the tiles upon the bars, after the reinforcements have been positioned, and without movement of the tiles end-wise of the bars.

4. A composite concrete and tile floor slab, comprising a system of multiple-tile, permanent-load sustaining arches, and a system of reinforced concrete ribs; the arches being spaced apart, end from end, in rows, each row constituting a succession of spans, and the concrete ribs being fills which lie between and which bond one to another the opposed ends of the arches in the several rows; the reinforcements for the concrete ribs comprising open-work webs set upright in the plane of the slab, and bars secured to and projecting laterally from the webs serving as seats for the ends of the arches, said bars being imbedded in the concrete above the base of the fills for service as true tension members therein; the several tiles which make up each multiple-tile arch being of shape and size to permit of independent manipulation thereof for seating the tiles upon the bars, after the reinforcements have

been positioned, and without movement of the tiles end-wise of the bars, and concrete fills between the several tiles of a multiple-tile arch for locking the same against displacement.

5. A composite concrete and tile floor slab, comprising a system of multiple-tile, permanent-load sustaining arches, and a system of reinforced concrete ribs, the arches being spaced apart, end from end, in rows, each row constituting a succession of spans, and the concrete ribs being fills which lie between and which bond one to another the opposed ends of the arches in the several rows; the reinforcements for the concrete ribs comprising open-work webs set upright in the plane of the slab, and bars secured to and projecting laterally from the webs serving as seats for the ends of the arches, said bars being imbedded in the concrete above the base of the fills for service as true tension members therein; the several tiles which make up each multiple-tile arch being of shape and size to permit of independent manipulation thereof for seating the tiles upon the bars, after the reinforcements have been positioned, and without movement of the tiles end-wise of the bars, and concrete fills between the several tiles of a multiple-tile arch for locking the same against displacement, said last-mentioned fills being permanent-load sustaining concrete ribs.

THEODORE BARBATO.
